William Garten, Baltimore, Md., assignor to
Owens-Illinois Can Company, Wilmington,
Del., a corporation of Delaware

Application May 23, 1939, Serial No. 85,151

Term of patent 7 years

To all whom it may concern:

Be it known that I, William Garten, a citizen of the United States, residing at Baltimore, in the State of Maryland, have invented a new, original, and ornamental Design for a Bread Box, of which the following is a specification, reference being had to the accompanying drawing, forming a part thereof.

In the drawing the figure is a perspective view of a bread box showing my new design. The

end wall not shown has substantially the same appearance as the end wall illustrated in the drawing. The flower-like surface decoration appears only on the front face, although the fine stripes continue down the rear wall.

I claim:

The ornamental design for a bread box, substantially as shown and described.

WILLIAM GARTEN.
